LIQUID MIXING APPARATUS

Clifford B. Terry, Flushing, N. Y., assignor to
 Lily-Tulip Cup Corporation, New York, N. Y.,
 a corporation of Delaware

Application May 15, 1941, Serial No. 393,501

5 Claims. (Cl. 259—108)

This invention relates to liquid mixing apparatus; and more especially to such apparatus for use in mixing drinks in the manner employed at soda fountains and the like. The invention is more particularly intended for use in conjunction with single service containers such as paper cups and receptacles.

Heretofore drink-mixing devices have been known wherein metal containers were employed with suitable provision for supporting the same after they have been moved to mixing position on the device. It has also been proposed to employ paper receptacles in conjunction with said mixing devices wherein a fixed stop is provided on the mixing device standard at such level that after the receptacle has been raised to the desired mixing position the fixed stop engages a flange on the bottom of the receptacle to support it in mixing position.

The chief purpose of this invention is to provide a more secure and suitable means for positioning and supporting a paper receptacle on said mixing devices and to facilitate the removal of said receptacle therefrom after the mixing operation is completed. More especially the purpose of the invention is to provide such means adapted to handle one-piece paper cups and the like receptacles which heretofore have been incapable of practical use on known devices.

The invention consists in the novel features, arrangements and combination of parts embodied by way of example in the apparatus hereinafter described as illustrating the present preferred form of the invention, and the invention will be more particularly pointed out in the appended claims.

Further objects and advantages of the invention will more fully appear from the following description taken in connection with the accompanying drawings, which show by way of example the preferred embodiment of the invention and in which:

Fig. 1 shows a perspective view of the mixing apparatus;

Fig. 2 shows a side elevation, partly in section, in conjunction with a one-piece paper cup and a flanged extension thereof jointly providing a mixing receptacle;

Fig. 3 is a cross-sectional view of a segment of the device illustrating the relative position of certain of the parts and is taken substantially on line 3—3 of Fig. 2;

Fig. 4 is a front elevation, somewhat enlarged, and showing further details of certain features of the invention;

Fig. 5 is a side elevation of the part shown in Fig. 4 but with the parts in a different position; and

Fig. 6 is a vertical, sectional elevation showing further details of certain features of the invention with the composite receptacle in raised position indicated by the dotted lines shown in Fig. 2.

Referring to the drawings, and more particularly to Fig. 1; the numeral 1 designates a standard serving as a supporting pedestal for the device and carrying fixed adjacent its upper end an electrical motor 2 to the armature of which is carried a depending mixing arm or device 3 adapted to be rotated upon actuation of the motor 2. The motor is preferably provided with a two-speed switch 4 and is supplied with current by the usual plug-in cord (not shown) through which electrical current is supplied to the motor under control of a suitable electrical switch designated by reference to its movable portion 5 (Figs. 3, 4 and 6). The standard 1, motor 2, mixing arm 3 and switches 4 and 5 represent a general structure well known in the art and not claimed per se as my invention.

The standard 1 carries rigidly secured thereto (Figs. 3 and 1) vertically spaced apart plates 6—6' to the respectively opposite edges of which are secured a pair of channel members 7—7' providing a track with guideways for receiving the rearwardly and inwardly turned oppositely disposed edges of the carriage plate 8 constructed and arranged to slide vertically on said track. A downwardly extending finger or hook 9 is secured adjacent the upper edge of the plate 8 and constructed and arranged to receive the upper lip of a mixing receptacle (see also Fig. 6). To the rear of the plate 8 there is rigidly secured a dependent strut or longitudinal carriage member 10 (see also Figs. 4 and 6) the upper end of which is provided with a rearwardly extending abutment portion 11 in register to engage the switch portion 5 which is normally resiliently held downward in off position and is adapted to be moved to closed position by the upward movement of the abutment 11. The lower end of the strut 10 is provided with a forwardly extending portion 12 which carries rigidly secured thereto a bottom support designated in its entirety as 13 and providing a substantial semi-circular seat portion 14 and an arcuate flanged back portion 15; the seat portion 14 being constructed and arranged to preferably extend beyond the diameter of the mixing receptacle such as the one-piece paper cup 16 (Figs. 6 and 2) and the arcuate back portion or flange 15 providing the lateral

support for said paper receptacle. Preferably the paper cup 16 is of a size adapted for the service of mixed drinks, and in order to prevent spilling of the drinks during mixing a sleeve extension 17 is provided, preferably made of metal, and provided with a reduced lower portion 18 for engagement within the lip of the cup 16 and with an upper lip portion 19 for engagement beneath the hook 9. It will be understood that the paper receptacle 16 and the sleeve extension 17 jointly serve as a mixing receptacle.

The lower plate 6' (Figs. 1 and 4) extends from the right outwardly beyond the track 7' and carries rigidly secured thereto the lower end of a spring arm 20 which extends upwardly and whose outer end is offset and constructed and arranged to provide a detent portion having an upper supporting portion 21 and a downwardly and inclined face 22, the detent passing through a slot formed in the track member 7' and being positioned and arranged so that the portion 21 comes into supporting engagement with a lug 23 carried on the carriage plate 8 when the carriage is in raised position (Fig. 5), to bring the receptacle into the dotted position indicated in Fig. 2; and when the detent is moved rearwardly to withdraw it from the lug 23 to permit the carriage to move downwardly. A bracket 24 is rigidly secured to the arm 20 and carries on its outer surface an engageable plate 25 disposed adjacent the carriage plate 8 and in such position as to be readily engageable by the hand of the operator which is used in grasping the receptacle to remove it from the mixing apparatus. To further facilitate the ready engagement of the plate 25 it is inclined outwardly and upwardly (Fig. 5). A stop 26 is provided for limiting the rearward movement of the arm 20 and detent 21.

Operation

From the foregoing, it will be readily understood that when it is desired to mix a drink from ingredients placed within the paper receptacle 16 and with the sleeve 17 positioned as an extension to the said paper receptacle or cup, the operator grasps the paper cup 16 in one hand, inserts the lip 19 of the receptacle beneath the finger 9 (Fig. 1), slides the bottom of the cup on the seat portion 14 against the back portion 15 and still grasping the cup moves his hand upwardly; whereupon the carriage 8 with the cup positioned thereon is moved upwardly, the abutment 11 engaging the switch 5 and moving it to closed position to thereby start the operation of the motor 2 and the rotation thereby of the stirring arm 3, and at that time the surface 22 of the detent has been over-ridden by the lug 23 and the upper or supporting face 21 of the detent has been moved into supporting position beneath the lug 23 to lock the carriage in its raised position, whereupon the operator removes his hand and the mixing proceeds. After the mixing has been completed, the operator with one movement of his hand presses against the plate 25 and grasps the cup 16, the carriage is permitted to freely move downwardly and then the cup moved downwardly to remove it entirely from the carriage, the sleeve 17 is removed and the drink is ready to be served.

Having thus described the invention with particularity with reference to the preferred embodiment of the same, it will be obvious to those skilled in the art, after understanding my invention, that changes and modifications may be

made therein without departing from the spirit and scope of the invention, and I aim in the appended claims to cover such changes and modifications as are within the scope of the invention.

5 What I claim is:

1. In a liquid mixing apparatus having a standard, a motor, a downwardly extending mixing arm rotatable by said motor and a switch for actuating said motor, the combination of a vertically movable carriage mounted on said standard for movement relative thereto and providing a bottom support having a back and a seat constructed and arranged to provide a lateral and vertical support for a receptacle bottom and said carriage also providing a hook for removable engagement with the top of said receptacle, an abutment portion carried on said carriage and constructed and arranged to move into actuating engagement with said switch upon the upward movement of said carriage, mechanism apart from said abutment for locking said carriage in upward position and provided with a release positioned adjacent said receptacle position for engagement by the hand of the operator used in removing the receptacle.

2. In a liquid mixing apparatus having a standard, a motor, a downwardly extending mixing arm rotatable by said motor and a switch for actuating said motor, the combination of a carriage for holding a receptacle and providing a bottom support and lateral support for the bottom and top portions of said receptacle, said carriage being mounted on said standard for vertical movement upwardly and downwardly and engageable with said switch for actuating the same to respective closed and open positions so as to effect the operation of said motor when the carriage is in raised position and to stop the motor when said carriage is in lowered position, releasable mechanism apart from said switch actuating means for holding said carriage in said raised position.

3. In a liquid mixing apparatus having a standard, a motor, a downwardly extending mixing arm rotatable by said motor and a switch for actuating said motor, the combination of a carriage for holding a receptacle and providing a bottom support and vertically spaced lateral supports for the respective bottom and top portions of said receptacle, a vertically extending track secured to said standard, said carriage being mounted on said track for vertical movement thereon and being provided with a portion engageable with said switch for actuating the same, an upwardly extending spring arm fixed at its lower end to said standard and carrying at its upper end a detent with an upper supporting portion for locking engagement beneath a cooperating portion of said carriage and a downwardly and inwardly inclined face in the path of movement of a cooperating portion of said carriage, said arm carrying a manually engageable portion disposed adjacent said carriage for the release of said detent by the hand of the operator used in removing said receptacle.

4. In a liquid mixing apparatus having a standard, a motor, a downwardly extending mixing arm rotatable by said motor and a switch for actuating said motor, the combination of a vertically movable carriage mounted on said standard for movement relative thereto and providing a bottom support having a back and a seat constructed and arranged to provide a lateral and vertical support for a substantial area

of a one-piece paper receptacle bottom and said carriage also providing a hook constructed and arranged for removable engagement with the top of a sleeve extension for said paper receptacle, an abutment portion carried on said carriage and constructed and arranged to move into actuating engagement with said switch upon the upward movement of said carriage, mechanism independent of said abutment for locking said carriage in upward position and provided with a 5 release positioned adjacent said receptacle position for engagement by the hand of the operator used in removing the receptacle.

5. In a liquid mixing apparatus having a standard, a motor, a downwardly extending mixing arm 10 rotatable by said motor and a switch for actuat-

ing said motor, the combination of a carriage for holding a receptacle and providing a bottom support and lateral support for the bottom and top portions of said receptacle, said carriage being mounted on said standard for vertical movement upwardly and downwardly and providing an abutment portion engageable with said switch for actuating the same to respective closed and open positions so as to effect the operation of said motor when the carriage is in raised position and to stop the motor when said carriage is in lowered position, releasable mechanism apart from said switch actuating means for holding said carriage in said raised position.

CLIFFORD B. TERRY.
